A. F. BEIMDIK.

CIRCUIT CLOSER.

APPLICATION FILED APR. 10, 1919.

1,354,875.

Patented Oct. 5, 1920.

UNITED STATES PATENT OFFICE.

AUGUST F. BEIMDIEK, OF ST. CHARLES, MISSOURI, ASSIGNOR TO AMERICAN CAR AND FOUNDRY COMPANY, OF NEW YORK, N. Y., A CORPORATION OF NEW JERSEY.

CIRCUIT-CLOSER.

1,354,875.

Specification of Letters Patent.

Patented Oct. 5, 1920.

Application filed April 10, 1919. Serial No. 288,989.

To whom it may concern:

Be it known that I, AUGUST F. BEIMDIEK, residing at St. Charles, Missouri, and being a citizen of the United States, have invented 5 certain new and useful Improvements in Circuit-Closers, of which the following is a full, clear, and exact description, such as will enable others skilled in the art to which it appertains to make and to use the same, 10 reference being had to the accompanying drawings which illustrate the preferred form of the invention, though it is to be understood that the invention is not limited to the exact details of construction shown 15 and described, as it is obvious that various modifications thereof within the scope of the claims will occur to persons skilled in the art.

In said drawings:

20 Figure 1 is a central vertical section through the expansion drum of a car heating system with my improved circuit closer applied in a horizontal position, and a dia-grammatic showing of a common signaling circuit;

Fig. 2 is a central vertical section through my improved circuit closer, the float and its supporting means being shown in elevation;

30 Fig. 3 is a front elevation of the contact plates of my improved circuit closer; and

Fig. 4 is a view showing my improved circuit closer as applied in a vertical position.

This invention relates to circuit closers, and more particularly to a float operated 35 circuit closer for use in connection with the expansion drums of car heating systems.

An object of my invention is to provide a float operated circuit closer that may be applied to the expansion drums of car heating 40 systems now in use in order that an alarm may be given when the water in the drum falls below a predetermined level. For this purpose, my invention comprises a circuit closer mounted on a plug designed to fit the 45 usual plug openings of the expansion drums and a float, of such dimensions as to readily pass through the plug openings for operating the circuit closer, the whole being assembled without the drum and applied as a unit.

50 In the drawing, 1 designates the usual cast expansion drum of a car heating system having inlet and outlet pipes 2 and 3 and plug openings 4 and 5. Opening 4 is, in

Fig. 1, closed by the usual plug 6, and in 55 opening 5 is inserted my improved circuit

closer 7. From the circuit closer 7 wire 8 leads to signal 10, a switch 9 being provided for cutting the signal out of service. From the signal 10, a wire 11 leads to battery 12 and from battery 12 a wire 13 leads to 60 the circuit closer 7. Joining wires 8 and 13 is a wire 14 containing a normally open switch 15 which constitutes a shunt around the circuit closer 7 and serves as a means for testing the battery 12 and signal 10. 65

The circuit closer 7 comprises a plug 16 screw threaded to fit the plug opening 5 and provided with an enlarged angular portion 17 for engagement with a wrench. The outer portion of the plug is bored to form a 70 chamber 18 and from the chamber 18 there extends a central longitudinal bore 19. In the chamber 18 is threaded a plug 20 provided with semi-circular contact plates 21 and 22 insulated from the plug and each 75 other by the insulation 23 and 24. Covering the outer end of the plug 20 is a hood 25 which is held to the plug 16 by the collar 26, the plug 16 and hood 25 serving as a casing for the plug 20 and the contact plates 21 and 22. Through an opening 34 in the hood 25 and longitudinal bores 35 in the plug 20, the wires 8 and 13 are led to the contact plates 21 and 22. 80

To the inner end of the plug 16 is attached 85 a rod 28 carrying a bracket 29 in which is pivoted the lever 30. To one end of the lever 30 is secured a link 31 which is connected at its other end to a rod 32 mounted to reciprocate in the bore 19 of the plug 16. 90 To the other end of the lever is secured the float 33. From Fig. 1 it will be seen that a lowering of the water level in the drum will cause a movement of the float 33 which will operate lever 30 and link 31 to move the rod 32 to engage the contact plates 21 and 22, bridging the gap between these plates and completing the circuit for the alarm. To adjust the circuit closer to the predetermined level, the plug 20 is rotated, thus 95 changing the distance the rod 32 must move before engaging the contact plates. In order to insure proper contact, the end of the rod 32 is made conical and the contact plates are provided with corresponding recesses. 100

To adapt the structure for application in a vertical position, a modified form of lever 30 can be used as shown in Fig. 4.

What I claim is:

1. In a device of the type described, the com- 110

- combination of a drum having an opening, a chambered plug adapted to be threaded into said opening in said drum, a float pivotally mounted on said plug and adapted to pass through said opening, a second plug mounted in the chamber of said first plug, contacts carried by said second plug and a rod passing through said first plug and operated by said float to engage said contacts.
2. In a device of the type described, the combination of a drum having an opening, an insertible device adapted to be applied as a unit comprising a plug adapted to be fitted

to the opening in the drum, a float pivotally mounted on said plug and adapted to be inserted through the opening in the drum, a second plug inserted in said first plug, contacts carried by said second plug and means operated by said float to connect said contacts.

In witness whereof I have hereunto set my hand in the presence of two witnesses.

AUGUST F. BEIMDIEK.

Witnesses:

GEORGIA BELDING,
BELLE TUTTLE.
